UNITED STATES PATENT OFFICE.

HENRY DOHERTY AND JOSEPH WADSWORTH, OF PATERSON, NEW JERSEY.

DESIGN FOR A HANDKERCHIEF.

SPECIFICATION forming part of Design No. 13,922, dated May 22, 1883.

Application filed April 6, 1883. Term of patent 3½ years.

To all whom it may concern:

Be it known that we, HENRY DOHERTY and JOSEPH WADSWORTH, citizens of the United States, and residents of Paterson, Passaic county, State of New Jersey, have invented a new and original Design for Handkerchiefs, of which the following is a specification, reference being had to the accompanying drawing, forming a part thereof.

10 A represents the body or groundwork of the handkerchief, having a figure, B, formed in each of its corners, which figures form complete a cat's head and face, which incline somewhat inwardly.

15 The color of the handkerchief is immaterial, but may be of any color desired and suitable therefor.

Having described our new and original design for handkerchiefs, what we claim, and desire to secure by Letters Patent, is—20 The handkerchief A, having a figure, B, composed of tufts a, tentacles b, lips c, nose d, eyes e, and ears f, formed in each corner of the same, substantially as shown.

HENRY DOHERTY.
JOSEPH WADSWORTH.
